PHONOGRAPH TONE ARM OR THE LIKE

Maurice M. Palo, Conneaut, Ohio

Application December 24, 1949, Serial No. 6,840

Term of patent 7 years

(Cl. D26—14)

To all whom it may concern:

Be it known that I, Maurice M. Palo, a citizen of the United States, residing at Conneaut, in the county of Ashtabula and State of Ohio, have invented a new, original, and ornamental design for a Phonograph Tone Arm or the like, of which the following is a specification, reference being had to the accompanying drawing, forming a part hereof.

Fig. 1 is a perspective view of a phonograph tone arm or the like, showing my new design;

Fig. 2 is a top plan view thereof;

Fig. 3 is a side elevational view;

Fig. 4 is a fragmentary side elevational view taken at lines 4—4 of Fig. 2;

Fig. 5 is a rear elevational view taken at the lines 5—5 of Fig. 2; and

Fig. 6 is a cross sectional view thereof taken at lines 6—6 of Fig. 2.

I claim:

The ornamental design for a phonograph tone arm or the like, as shown.

MAURICE M. PALO.
